UNITED STATES PATENT OFFICE.

EDWARD CYRIL BOWDEN-SMITH, OF BROCKENHURST, ENGLAND.

PNEUMATIC EJECTOR.

1,144,806.

Specification of Letters Patent. Patented June 29, 1915.

Application filed November 3, 1913. Serial No. 798,914.

To all whom it may concern:

Be it known that I, EDWARD CYRIL BOWDEN-SMITH, of Carey's, Brockenhurst, Hampshire, England, engineer, have invented certain new and useful Improvements in and Relating to Pneumatic Ejectors, of which the following is a specification.

This invention relates to the utilization of pneumatic ejectors of the type employed for raising a liquid or semi-liquid, by means of compressed air.

Briefly, the ejectors in common use for raising sewage consist of spherical vessels, into which the liquid flows by gravitation.

15 When full a weighted float rises on the surface, to this float is attached a rod passing through the crown of the ejector, which actuates certain valves allowing compressed air to exert the necessary force directly on 20 the surface of the liquid, till it has been discharged through the outlet pipe at the base of the ejector, eventually rising through a main to the required level. By this means solid matter is first driven out of the ejector.

25 When the discharge is completed the weighted float falls, closing the air valve and opening the exhaust, the compressed air escaping to the atmosphere. They are usually worked in pairs, and are arranged in such a 30 manner that although they are entirely automatic they are both alternating or differential in action, as circumstances require.

The object of this invention is to utilize a part of the exhaust from the ejector and to 35 use it in an air engine to recompress a part of the exhaust to be used in the ejector again.

An ejector made in accordance with this invention is provided with a motor adapted to be operated by the exhaust from the 40 ejector for the purpose of recompressing a portion of the air from the exhaust of the ejector to a pressure at which it can be used again and an arrangement of valves and parts for automatically controlling and operating the mechanism. The motor and the 45 compressor may each have one or more cylinders and these may be single or double acting.

The drawings show apparatus embodying 50 the features of this invention.

Figure 1. is a section showing the general arrangements of parts. Fig. 2. is a similar view at right angles to Fig. 1. Fig. 3. is a sectional plan. Fig. 4. is a diagram showing pneumatic control. Fig. 4^a is an enlarged detail of valve 13.

It will be seen that the air motor compressor A consists of two double acting air cylinders *a* and *b* on either hand, with the single acting compressor *c* in the center. 60 They are mounted on a bed plate *d*, which forms the bottom cover of the two air cylinders, with a similar plate for the top cover, on which are cast the cross head guides. To this top cover are bolted two A frames *e* 65 which support the crank shaft *f* and two fly wheels *g* and *h*. The motor compressor used in connection with this invention is described in my British specification No. 11,381 of 1913. 70

For the purpose of explanation, we will now assume that an ejector has finished discharging, the various automatic valves in their correct position and the exhaust air from the ejector flowing through the pipe to 75 the air motor. The exhaust air from the ejector passed into and fills a jacket surrounding the compressor itself. This jacket, by reason of the hot walls of the compressor, will tend to dry and warm the air 80 before it passes to the air motor cylinders. The air performs its work expansively till at the correct moment the exhaust valve from the ejector opens and the exhaust air which is now at a lower temperature, flows 85 through the exhaust pipes to the suction chamber of the compressor. The cubic capacity of the compressor cylinder being small, relatively to that of the motor cylinders, the compressor cylinder will not have 90 sufficient capacity to draw in the whole of the exhaust air from the two motor cylinders, consequently what is not required will escape from an exhaust on the top of the motor to the atmosphere. 95

We will follow the air in its course from its entrance by the main to its indefinite consumption, or escape to the atmosphere. It must be understood, that in this system, a certain percentage of the air can be used an 100 unlimited number of times, but the air which is not required escapes automatically either by the atmospheric pipe, from the suction chamber of the compressor or by the exhaust valve hereinafter termed the differential exhaust valve. The pressure air for operating the ejectors enters by the inlet pipe *j* flowing down the air main *k* it passes through the dirt box *m* and discharges into the receiver *n* after passing the reflux valve *o*. From 110 this receiver it flows upward by the pipe *n'* to the alternating valve *p* then passes to

either of the automatic valves q and down to the ejectors r r' by the pipe q' . Having discharged the liquid from the ejector the air returns through the same pipe q' to the automatic valves q and thence to the differential exhaust valve s . This being closed the air finds a passage down the pipe n' leading to the non-return valve u , after passing this valve the air travels through the pipe t to the motor A, by a connection not shown, which recompresses a part of the air and discharges the same into the receiver n , by the pipe n' , after passing the non-return valve v , the connection between the compressor and the pipe n' not being shown. The air that is not required by the compressor escapes from the compressor exhaust on the engine, up the pipe w to the atmosphere.

The valves are operated by compressed air flowing through small pipes, and for the purpose of explanation a diagram (not to scale) is given. In Fig. 4 the cross hatching indicates parts filled with compressed air. In the ejector not hatched compressed air is about to discharge liquid from the ejector. In the diagram the right-hand ejector has just discharged, and the left-hand ejector is about to do so. Taking the left-hand ejector, it can be seen the float 3 has risen throwing over the slide valve 4 which has opened the port 5 allowing the compressed air from the main supply pipe 11, which is connected to the slide valve chest to pass up the pipe 6 and drive over the automatic valve q closing the exhaust port 7 and opening the air port 8. The air is able to drive over the automatic valve, as described since it will be observed that at the same time the slide valve 4 opens the port 5, it opens the port 9 to exhaust thus releasing the pressure from the pipe 9^a . Again this releasing of pressure allows the alternating valve p to be driven over by the pressure from the opposite end, and so opening the port 10 allowing direct communication between the main air inlet 11 and the connecting mains 12 and the ejector r . This releasing of pressure allows of the fall of the intercepting valve 13 which closes the port 14 the valve being held tightly on its seat by the pressure in the pipe 15. It will be observed that the differential exhaust-valve s is open allowing communication from the automatic valve q and exhaust port 7 which is closed, to the atmosphere. All these valves remain in this position while the air is discharging the liquid in the ejector r . This being completed the float 3 falls, the slide valve 4 opens the port 9 to air pressure and opening port 5 to an exhaust, not shown. The pressure is released on one end of the automatic valve q and the said valve is driven over from the opposite end by the pressure passing up the pipe 9^a from the port 9. The air port 8 is closed and the exhaust port 7 is opened. Again at the same time alternating valve p , in spite of the pressure in the pipe 9^a and 17 (which it will be seen is in connection with port 9) remains where it is, owing to the pressure at the opposite end, but the intercepting valve 13 is forced upward by the pressure opening the port 14 and allowing the differential exhaust valve s to be driven over. The air having already escaped from the opposite end of s through the port 14 to the automatic valve and thence to the motor by way of pipe t . Again this closes the port 18, which compels the exhaust air from the ejector instead of finding its way to the atmosphere to flow through the valve u and pipe t to the air motor; assuming that this ejector which has just discharged fills again before the other becomes full the alternating valve p remains where it is, the differential exhaust s remains where it is, the automatic valve q opens the air and closes the exhaust while the intercepting valve 13 opens and closes at the same time as the movement of the slide valve 4, but the passage of the air does not operate the differential exhaust as the valve is already in its right place and remains so until the other ejector comes into action. As long as this ejector alone fills and empties this action continues. When the other ejector fills and has discharged the liquid it closes its own differential exhaust and it cannot fail to open the exhaust for the other, whether there is any exhaust air remaining to be liberated or not so by this simple means, we secure a perfect automatic, safety attachment, in the event of failure of the motor. In other words, either ejector will release the exhaust for its fellow and so automatically "cut out" the motor in the event of failure. In the event of valve 13 being closed before the valve s has been driven over, and thereby the exhaust being prevented from escaping, the air contained in the cylinder s can exhaust through a port in the casing 14^a . This port is closed by the stem of the valve 13 when the valve is raised, but when the valve is closed the exhaust can escape from the valve s through a channel 13^a in the stem of the valve and out at the port, the stem of the valve thus acting as a slide valve to open and close the port.

The use of the differential exhaust is to keep the exhaust pipe closed so that the air will flow to the motor. The object of introducing the intercepting valve, it will be seen, is to prevent the differential exhaust from being driven over till the liquid in the ejector has been discharged. In other words it intercepts the passage of the air and delays the action of the differential exhaust.

If there were no intercepting valve, the differential exhaust would drive over at

once at the same time as the alternating valve, and the exhaust from the ejector that had just discharged would at once escape to the atmosphere instead of being stopped 5 and so flowing to the motor. By opening the two by-pass stop valves the ejectors return to the simple conditions of working and are then as independent of the motor and accessory valves as if they did not exist.

10 It is obvious that by this simple automatic device either ejector can "cut out" the motor and at the same time safeguard their own continuous working.

What I claim and desire to secure by Letters Patent is:—

15 1. In pneumatic ejectors the combination of a motor adapted to be operated by the exhaust from the ejector; an air compressor for the purpose of recompressing a portion 20 of the exhaust and means for opening and closing the exhaust ports.

20 2. In pneumatic ejectors the combination of a motor adapted to be operated by the

exhaust from the ejector; an air compressor for the purpose of recompressing a portion 25 of the used air; a differential valve for opening and closing the exhaust ports and means for conducting the exhaust air to the motor and compressor.

3. In pneumatic ejectors the combination 30 of a motor adapted to be operated by the exhaust from the ejector; an air compressor for the purpose of recompressing a portion of the used air; a differential valve for opening and closing the exhaust ports and an intercepting valve for delaying the return of the differential valve and allowing one 35 ejector to be discharged while the other is exhausting to the air motor.

In witness whereof, I have hereunto 40 signed my name in the presence of two subscribing witnesses.

EDWARD CYRIL BOWDEN-SMITH.
